UNITED STATES PATENT OFFICE

157,912

DIRECTED BEAM LIGHT UNIT

Frank W. Schwinn, Chicago, Ill.

Application April 1, 1948, Serial No. 145,467

Term of patent 14 years

(Cl. D48—32)

To all whom it may concern:

Be it known that I, Frank W. Schwinn, a citizen of the United States, residing in Chicago, in the county of Cook and State of Illinois, have invented a new, original, and ornamental Design for a Directed Beam Light Unit, of which the following is a specification, reference being had to the accompanying two sheets of drawings, forming part thereof.

In the drawing:

Fig. 1 is a side elevational view of a directed beam light unit showing my new design;

Fig. 2 is a top plan view of light unit shown in Fig. 1;

Fig. 3 is a front elevational view of the light unit shown in Figs. 1 and 2; and

Fig. 4 is a rear elevational view of the same.

The portions of Figs. 1, 3 and 4 which are depicted in dotted lines are for illustrative purposes only.

I claim:

The ornamental design for a directed beam light unit, substantially as shown and described.

FRANK W. SCHWINN.
